Primary Examiner — John Windmuller*Assistant Examiner* — John R Yeh(74) *Attorney, Agent, or Firm* — Sheridan Ross P.C.(57) **CLAIM**

The ornamental design for a remote control device with an icon, as shown and described.

DESCRIPTION

The FIGURE is a front plan view of a remote control device with an icon.

The claimed design is flat and with all elements coplanar. The broken lines showing a remote control device are for the purpose of illustrating environment and form no part of the claimed design.

1 Claim, 1 Drawing Sheet(56)
